HOISTING MECHANISM

Harvey W. Ball, Alliance, Ohio, assignor to The
Morgan Engineering Company, Alliance, Ohio

Application November 5, 1942, Serial No. 464,637

1 Claim. (Cl. 254—184)

This invention relates to hoisting mechanism for overhead trolleys, and more particularly to cranes having an improved arrangement for transmitting the power from the motive force to the winding drums.

One of the objects of the invention is to provide hoisting mechanism including a pair of drums and a pair of motors that are entirely inter-connected and can be operated with both motors acting simultaneously, or in the event that one motor becomes incapacitated, can be operated by the other motor.

Another object is to supply a mechanism of this character in which the connecting means between the motors and drums is so constructed and arranged as to equalize forces and balance the structure so as to effectively take care of torque, etc.

Another object is to furnish a hoisting mechanism of this type in which the motors as well as intermediate shafts may be effectively braked.

Another object is to provide crane hoisting mechanism in which the cables are wound about the drum and pulley in one direction only, so as to prevent reverse bending of the cables.

With the foregoing objects outlined and with other objects in view which will appear as the description proceeds, the invention consists in the novel features hereinafter described in detail, illustrated in the accompanying drawings, and more particularly pointed out in the appended claim.

In the drawings:

Fig. 1 is a plan view of my improved mechanism.

Fig. 2 is an end view.

Fig. 3 is a view of one of the drums shown detached, and illustrating the manner in which it is associated with the sheave wheels.

Fig. 4 is a diagrammatic side elevation of the drum and sheave wheels, with one of the cables wound about the same.

Referring to the drawings, 5 designates the rectangular frame of the crane trolley, having cross-supports 6. At each end of the frame, a drum 7 is rotatably mounted at 8 on a pair of the cross-supports, and each drum has a fixedly connected relatively large gear wheel 9.

Parallel shifting 10 extends along opposite sides of the drums and is journalled in bearings

on the cross-supports, as indicated at 11 and 12, and each shafting preferably consists of a relatively long shaft 13 and a shorter shaft 14, connected together by a flange coupling 15.

5 The shafting is provided with pairs of small gears 16, each pair meshing with one of the drum gears 9.

Each shafting is also provided with a larger gear 17 meshing with a smaller gear 18 fixed to a short shaft 19, journaled in bearings 20 on adjacent cross-supports. A larger gear 21 is fixed to each short shaft and is driven by a smaller gear 22 on a motor driven shaft 23, the latter rotating in bearings 24 supported by adjacent cross-bars 6.

A motor 25, preferably of an electrical type, has its shaft 26 connected to the shaft 23 by a flexible coupling 27 which may be of the "Fast" type. Such couplings compensate for misalignment of the shafts 23, 26, and are very efficient where high speeds are transmitted from one shaft to another.

25 A brake 28 for each of the motors is preferably electrically operated, and in order to distribute the braking on the transmission mechanism between the motors and the drums, a separate similar brake 29 is provided for each of the shafts 19. In practice, I have employed magnetic brakes, each brake 28 being synchronized with the brake 29 which is between it and its associated drum, and both brakes are automatically released when the motor is energized for hoisting or lowering.

30 From the arrows applied to the gears, it may be seen that both motors can simultaneously drive the drums, or either motor can drive both drums while the other motor is idle.

It may be seen from Fig. 3 that each drum is associated with a pair of cables 30 which are wound about the drums in a clock-wise direction and have terminals anchored thereto as indicated at 31. From the drum, the cables descend and pass about upwardly and downwardly movable sheave wheels 32 carried by a support 33 having oppositely extending arms 34. From the sheaves 32, the cables extend upwardly, as indicated at 35, thence about sheave wheels 36 journaled in the frame of the trolley, as indicated at 37 in Fig. 2. Each cable then passes again around a sheave wheel 32 and a sheave wheel 36, and has 40 its other end secured to one of the arms 34, as

indicated at 38. From Fig. 4 it may be seen that each cable is bent in one way only.

From the foregoing it is believed that the construction, operation and advantages of the invention may be readily understood, and I am aware that changes may be made in the details disclosed, without departing from the spirit of the invention, as expressed in the claim.

What is claimed and desired to be secured by Letters Patent is:

In combination, a pair of hoisting drums spaced apart and in axial alignment, a first gear fixedly connected to each drum, a pair of shafts extending along opposite sides of said drums,

two pairs of second duplicate gears fixed to said shafting, each of the first gears meshing at diametrically opposite points thereof with a pair of the second gears, third gears fixed in their entirety to said shafting, a pair of short shafts positioned between the shafting and each provided with a gear meshing with one of said third gears, a brake acting on each short shaft, a pair of motors, each motor having a driven shaft, gearing connecting each motor shaft with one of the short shafts, and a brake acting on each motor shaft.

HARVEY W. BALL.
